TABULATING MACHINE

Paul M. Rainey, Montclair, N. J., assignor to
Combination Selector Company, Montclair,
N. J., a corporation of New Jersey

Application April 26, 1935, Serial No. 18,483

6 Claims. (Cl. 235—61.7)

This invention relates to new and useful improvements in tabulating machines.

The object of the invention is to provide a machine in which a plurality of compilations of data can be simultaneously obtained from a set of record members while the record members are fed through the machine.

A tabulating machine embodying the various features of the present invention is designed to use tabulating record members, such as cards of conventional form in which the desired information, numerical or otherwise, is recorded by means of punched holes. These holes may be located in any one of a plurality of locations in any or each of a plurality of positions or columns. Each position or column has at least 10 locations, at any one of which holes may be punched indicating the numeral digits 0, 1, 2, 3, 4, 5, 6, 7, 8 or 9. The machine herein described uses a card having 45 columns with locations for 12 holes in each column.

The machine is of about the size of two standard typewriters. It is motor driven, and is provided with a magazine into which the cards are placed in a horizontal position, one on top of the other, forming a stack. The machine feeds the cards from the bottom of the stack to a receiving pocket, depositing them in the same sequence in which they were placed in the magazine. The machine is provided with two adding heads each adjustable to accumulate numerical data from any group of adjacent columns of the cards placed in the magazine. Each adding head is under the control of an associated reading mechanism, including a matrix which makes it possible to accumulate numerical data from any classification of cards without the necessity for sorting or otherwise disturbing the original sequence of the cards.

The reading mechanism comprises feeling members or fingers which "read" the holes punched in the card while the latter is in the testing position. Whether or not numerical data is to be accumulated from a given card is controlled by means of standard record members or matrix cards. In the present embodiment of the invention two matrix cards are provided. In form these are similar to the tabulating cards placed in the magazine. A given matrix card is punched to indicate the specification of the classification for which accumulation is desired. Matrices thus prepared are compared by the machine with a pattern of pins (one set of pins being provided for each matrix) set up by the machine as the cards are fed from the magazine

to the receiving pocket. The position of each pin in each pattern is determined by the position of a hole in the corresponding column of each tabulating card as it is fed from the magazine. If all the pins in one of these patterns find holes in the matrix with which it is compared, then this indicates that the tabulating card last fed from the magazine is of the classification specified on a matrix and that accumulation of certain data is desired. If one or more of the pins fail to find holes in the associated matrix, then accumulation from that particular card is not desired on the accumulating mechanism associated with the matrix. The necessity of sorting the tabulating cards is entirely eliminated and the cards may be maintained in any convenient order. This makes it possible for the individual card to have a utility of place and for the file of cards to have a utility of arrangement.

In addition to controlling the selection of cards for the purpose of accumulating desired data, one or both of the matrices control also the performance of other functions.

1. The location and width of a notch in one edge of the matrix determines the particular columns on record cards from which data should be accumulated.

2. A notch in another position on the matrix causes the cards of a given classification, as determined by the matrix, to be thrown into a separate pocket.

3. A notch in another position causes the machine to print a translation of all tabulating cards of the classification determined by the matrix.

4. A notch in still another position permits a mechanical memory mechanism to control the adding head with which the particular matrix is associated to accumulate and print sub-totals of cards numerically arranged with respect to numerical indications in any desired columns.

By comparing the cards simultaneously with two or more matrices, a large variety of statistical data can be accumulated from a set of cards with great dispatch.

The matrices afford a fileable record of the functions performed by the machine. If once right, they are always right, wear and tear excepted, and therefore can be re-used whenever it is desired to secure similar information in similar form from similar cards. A file of these matrices may therefore constitute a record of clerical routine, relieving the operation of the necessity of setting the machine to do a particular job and

thus insure against human errors by substituting mechanical surety.

In the preferred embodiment herein disclosed, the matrix and the record members are of paper, and perforations represent the data or indicia which the machine tests or reads off the record members and compares with the matrix or matrices. Obviously, other types of cards or slugs may be used without departing from the spirit 10 of the invention.

A more complete understanding of the machine and the details of its operation will be obtained by referring to the following detailed description of its operation and the appended claims.

15 In the drawings, Fig. 1 is a side elevation of the tabulating machine;

Fig. 2 is a detail of the translating mechanism;

Fig. 3 is a longitudinal cross-section of the machine;

20 Fig. 4 is a detail of the mechanism controlling the dropping of the matrix mechanism;

Fig. 5 is a detail showing the mechanism for arresting the movement of the individual selecting bars;

25 Fig. 6 shows certain details in connection with the operation of the sorting mechanism;

Fig. 7 shows certain details for controlling the sorting operation;

30 Fig. 8 shows certain details in connection with sorting and the latches for maintaining the totalizer in the desired position;

Fig. 9 is a horizontal section through the gear reduction unit of the drive;

35 Fig. 10 shows certain details of the mechanical memory and the control of adding sectors, totalizer and sorting mechanism;

Fig. 11 shows part of the mechanism illustrated in Fig. 10 in a different position;

40 Fig. 12 is a front view of the tabulating machine with the adding mechanism eliminated;

Figs. 13, 14 and 15 show how different functions of the machine are controlled by notches in the matrix member, Fig. 13 being a sectional view along line 13-13 of Fig. 15;

45 Fig. 16 is a side elevation of a detail of the adding mechanism; and

Fig. 17 is a diagram illustrating the timing of the machine.

In reading the following detailed description of 50 the machine, Fig. 17 should be consulted. The curve represents the movement of carriage 26 (in inches) in response to the rotation of driving gear 13 (in degrees). The shaded ovals below the graph represent the occurrence of functions noted in the appropriate legends with respect to the position of the carriage.

The usual record cards 1 perforated in accordance with the statistical or other data to be tabulated are stacked within a supply magazine 2 fastened on a casting 3 projecting from the base 4 of the machine. A weight 5 is placed on the top card.

Power for operating the machine is supplied from a suitable motor (not shown) through a belt 6 (see Figs. 1 and 9) which rotates a pulley 7 freely mounted on shaft 8. As the pulley 7 rotates a gear 9 fastened thereto and also freely rotatable on shaft 8 rotates with it and rotates in turn a gear 10 mounted on a stub shaft 11 within 70 the frame 12 in which shaft 8 is also mounted. The other end of stub shaft 11 carries a small gear 12 which is in mesh with a gear 13 fastened to one end of shaft 8. Gear 13 will, therefore, rotate shaft 8. Fastened to the other end of shaft 75 8 is a cam 14 carrying a pin 15. During the rota-

tion of gear 13 a lever 16 pivoted to the gear at 17 (see Fig. 3) is moved around with it and rocks a link coupling consisting of two arms 18 and 19. 18 is pivoted at one end in a casting 20 attached to the base 4, to the end of which is pivoted at 21 the link 19. Intermediate the ends of link 18 is pivoted at 22 the free end of lever 16. The other end of link 19 is fastened to rod 23 mounted in two brackets like 24 projecting from bottom 25 of carriage 26 extending substantially the full length 10 and width of the machine. The rocking of the linkage 16, 18, 19 during the rotation of gear 13 will, therefore, cause the carriage 26 to reciprocate with respect to the frame of the machine, the linkage being introduced between the motive 15 power and the carriage in order to insure the quick return movement (from right to left, as shown in the drawings).

The carriage rides on rollers like 27 (Fig. 12) suitably supported in casting 3 by means of stub 20 shaft 28 (Figs. 1 and 10). Fastened to the front edge of the carriage 26 is a solid plate 29 (Fig. 5) of the same width as the carriage and in the front edge of plate 29 is fastened a plate 30 of the same width as plate 29, but having a lip overhanging 24 the edge of plate 29. Forty-six equally spaced strips 31 are anchored in the front edge of plate 29 at 32 below the overhanging lip of plate 30, the other ends of said strips 31 being anchored in a bar or strip 33 which again is of the same 34 length as the width of the carriage. Strip 33 constitutes the front edge of carriage 26. The spaces between adjacent strips 31 come directly under the perforations in the different columns of the cards 1, the lowermost card resting on the strips 31 when the carriage is in its back position. Through each space between adjacent strips projects a feeling member constituted by a spring 34, the lower end of each of which is fastened to the free end of a corresponding lever 35, pivotally 40 mounted at 36 on a frame 37 which rests on casting 3. The wire 34 is bent into a gooseneck and its free end 38 is bent at right angles and is, in the normal position of the carriage 26, held down with respect to the cards by means of a retaining 45 strip 39 fastened to the bottom of strip 33. As the carriage is moved to the right (Figs. 3 and 5), the projecting lip of plate 30, which is in alignment with the lowermost card 1a, pushes said card to the right through a gate 40 on magazine 50 2, which affords a clearance above the tops of the strips 31 just sufficient for the passage of a single card.

As the carriage is moved to the right, the retaining strip 39 frees the springs 34 and permits them to project upward against the bottom of the card which has been fed out of the magazine, in the present case card 1a. If the card is perforated in alignment with the upper end 38 of a spring 34, then the latter will project through 60 such perforation. During the further movement to the right of the card, the springs 34 having ends 38 which had found perforations, will rotate the associated lever 35 in a clockwise direction around the pivot 36 and the left-hand ends of such levers 65 35 will be caused to move upward within jaws 41 mounted on plate 37 and each will lift a roller 42 into engagement with a notched rack 43 in the lower face of a selecting bar 44 extending substantially the full length of the carriage. One 70 selecting bar 44 is provided for each space between strips 31, in the present case a total of forty-five and, therefore, one for each column on the cards in which perforations may occur. These feeling members 34 will, therefore, test each card

as it is being fed for the presence of indicia on the card in the various columns. The result of this card testing or reading operation will be communicated to the machine in the manner to be presently described.

The forty-five selecting bars 44 are frictionally held in the carriage 26 and are taken along with the carriage during its reciprocating movement until a bar 44 is arrested by a roller 42 and held

- 10 in the position to which it has been advanced at the time the spring 34, associated with the particular lever 35, happened to project through a perforation in the card. The unavoidable friction due to the weight of the selecting bars is sufficient 15 for operation at moderate speeds. To work at higher speeds sufficient friction is insured by springs attached to the carriage and pressing against the selecting bars. It will be seen, therefore, that when the carriage 26 has been moved 20 to its extreme right-hand position, some of the bars 44 will have moved with the carriage to their extreme right-hand positions, and others arrested in intermediate positions, the positions of the selecting bars indicating the pattern of the perforations in the card 1a that had been removed from the magazine.

Each of the tabulating bars 44 carries a matrix testing pin 45. These pins 45 are normally in alignment and will, therefore, upon the completion of the left-to-right stroke display a male pattern of the perforated pattern of the card selected. The nearer to the right-hand edge of card 1a the perforations occur, the nearer to the left-hand edge of Fig. 5 will the corresponding pin 45 be arrested. These pins 45 are below a matrix holder 46 between which a standard record or matrix card 47 is held. The matrix holder 46 is carried by a bracket 48 pivoted at 49 to the frame of the machine and is open on the operating side 40 of the machine. Its top and bottom plates are flared out to facilitate the inserting of the matrix. The matrix card 47 may be of the same size and shape as the cards and is divided into columns like the cards 1. It is perforated in accordance with the tabulation or statistical data that one may wish to read off the cards. In other words, one punches into the matrix a female pattern of all the information that it is required to obtain from the cards. Where, for instance, the cards have to do with a census and each card contains a large number of characteristic indicia of individuals, the matrix card 47 may be punched to select all the male individuals more than thirty years old who were born in the United States, are 55 at present employed, have dependents and were educated beyond the primary school grade, etc. A second matrix card 281 is punched in accordance with another group of statistical data and the card fed is compared with it through the agency 60 of a second set of pins like 283, one on each selector bar 44 which are also set into a male pattern representing the indicia on the card fed. I am enabled, therefore, to tabulate, list or otherwise 65 compile a plurality of different classes of statistical information while the cards are fed through the machine. The cards need not be specially classified and need not be run through the machine more than once. The matrix cards are punched in accordance with the desiderata and 70 the machine is operated without any special adjustment to perform the required operations.

As the carriage continues its movement in the right-hand direction the springs 34, the ends 38 of which have projected through perforations in the card 1a, will snap out of the perforations.

The lever 35 associated with each spring 34 which had been snapped out of its hole, may return to its normal position shown in Fig. 3, but roller 42 which had been lifted by the associated lever 35, will be wedged between a tooth of rack 43 on the 5 selecting bar 44 and the inclined surface 50 of the jaws 41, holding the tabulating bar 44 in its arrested position and preventing its further advance with the carriage.

As the carriage continues its movement in a 10 right-hand direction the card 1a passes under two rollers 51 (only one shown) hinged on a bar 52 by means of bracket 53 to the side of magazine 2 at 54. The bracket 53 is pulled towards the magazine by means of a coiled spring 55, the motion of the bracket 53 with respect to the magazine being limited by a leg 56 projecting from the bracket. A simple clutch consisting of a wire spring indicated at 56a is provided on each roller 51, permitting it to rotate in a counter-clockwise 20 direction but preventing clockwise rotation. Therefore, in the final stages of the right-hand movement of card 1a, rollers 51 will roll over the surface of card 1a.

Before the carriage reaches its end position to 25 the right and after the last perforation on card 1a has passed the gate 40, or the position on the card where there might be a perforation has passed the gate 40, the pin 15 (Figs. 1 and 4) on cam 14 engages lever 57 pivoted in a bracket 58 30 attached to the base 4. The lever 57 is pulled up against an adjustable stop 59 in a bracket 60 by a spring 61 attached to casting 3. The pin 15 will press down lever 57 against the tension of spring 61 and pulls down a link 62, fastened at 35 one end 63 to the lever, and at the other end 64 to a lever 65. The lever 65 is rotatably mounted on the shaft 49 (Figs. 1 and 4). The bracket 48 holding the matrix 46 may move with respect to the lever 65 to an extent limited by a screw 66 40 projecting through bracket 48. As the lever 62 is pulled down it will pull down the lever 65 and thus permit bracket 48 to fall by gravity.

If the perforations in the matrix 47 are in alignment with all the pins 45 positioned under 45 the matrix holder 46 in accordance with the perforated pattern of card 1a, then the matrix holder will drop far enough for the pins 45 to project through the lower and upper halves of the matrix holder and, of course, the perforations in the 50 cards. If the setting of pins 45 does not in every respect correspond to the perforations in the matrix, then at least one of the pins will find an obstruction preventing the dropping of the matrix holder 46 to its lowest position.

A stop 67 projecting through the free end of the matrix holder 46 cooperates with a bell-crank lever 68 (Figs. 1, 10, 11). These elements are shown in the normal position in Fig. 1. Fig 10 illustrates the condition when perforations in the 60 matrix 47 permitted the matrix holder 46 to drop into its lowermost position, wherein the stop 67 engages the upper end of bell-crank 68 and causes it to rock around its pivot point 69 in the frame, in which position it will be latched 65 by latch 70 pivoted at 71 in the frame and engaging an ear 72 projecting from the bell-crank 68. The right-hand leg 73 of the crank 68 will be tipped up as shown in Fig. 10. As shown in Figs. 1 and 11, in the normal position an ear 74 70 projecting from the free end 73 of the crank engages a catch 75 in a long bar 76 which controls the sorting of the cards. The bar 76 is mounted to perform a limited longitudinal movement in the frame of the machine. Bar 76 is urged to move

from left to right against stop pin 78 rigidly mounted in side projecting ear of lever 84 by means of a spring 79, one end of which is fastened to bar 76, and the other end of which is fastened to a lever 84 (Figs. 1, 6, 10 and 11). As the carriage 26 nears the end of its stroke, then, as shown in Fig. 6, a pin 81 projecting from the carriage 26, engages the lower end of a lever 82 and rocks it in a counter-clockwise direction around its pivot 83 on the frame. The upper end 82a of the lever 82 is hooked around a lever 84 pivoted at 85 in the frame and rotates the lever 84 in a counter-clockwise direction. The right-hand end of bar 76 is pivoted at 86 to one leg of a bell-crank 87 which in turn is pivoted at 80 to the lower end of lever 84. If bar 76 is free to move forward, the bell-crank 87 is moved to the right, pivoting around 85 with lever 84, but if bar 76 is not free to move to the right, bell-crank 87 is then turned counter-clockwise around pivot 80 with respect to lever 84 and in its extreme position misses the ear 89 on latch 90. The latch 90 is pivoted at 85 and is rotated in a clockwise direction by means of a spring 91 attached to the ear 89. Therefore, if bar 76 is held in its left-hand position, latch 90 will not be operated and will hold double-armed lever 92 in the position shown in Fig. 1.

If, however, as is assumed in the present case, the matrix comes all the way down and tilts arm 78 so as to release bar 76, the latch 90 will be lifted into the position shown in Fig. 10, and releases the double-armed lever 92 to be rotated by spring 93 around the pivot 94. The pivot shaft 94 carries a plate 95 shown in Fig. 5 in the latched-up position. In the latched-up position of the plate 95 the card 1a when released, as I shall presently describe, will fall in the pocket 96 (Figs. 1 and 3). In the unlatched position as shown in Fig. 10 the card would fall in the pocket 97.

During the forward movement of the carriage 26, link 98 (Figs. 1, 10 and 11) pivoted at 29 and a second link 99 also pivoted at 29, moved from left to right with the carriage, i. e., from the position shown in Fig. 1 into the position shown in Fig. 10, going through the intermediate position shown in Fig. 11. The left-hand end of link 98 is provided with a pin 100 which passes through a slot 101 in the lower end of a link 102, which in turn is pivoted at 103 to the free end of a crank 104 pivoted to a shaft 105, the operation of which will be described later. A link 106 is, at one of its ends, attached to pin 100 and is pivoted at its other end in bracket 107 on the base 4. Intermediate the ends of link 106 a pin 108 is guided within a slot 109 of a crank 110 pivoted at 111 to the frame of the machine. Similar links are associated with link 98 at the forward end of the machine. A pin 112 projecting from the end of link 98 passes through a slot 113 in the lower end of a link 114. The upper end of link 114 is pivoted at 115 to the end of a crank 116 which is fastened to a shaft 117 similar to shaft 105. The link 114 (see, for instance, Figs. 10 and 11), is provided with an ear 118 to which one end of a coiled spring 119 is attached. The other end of spring 119 is attached to ear 120 of a lever 121 pivoted at 122 to link 114. As best shown in Fig. 10, the lower end of lever 121 is cut out at 123. In the normal position shown in Fig. 1 this cut-away portion rests against pin 112 and prevents the pin from riding up in slot 113, thus imparting motion during the left-to-right movement of the carriage to crank 116 and thus rotates shaft 117.

Link 102 is similarly coupled through a spring 124 with a lever 125 which corresponds to lever 121 and which prevents pin 100 from riding up in slot 101 and causes, through the agency of crank 104, shaft 105 to rotate.

A link 126, the lower end of which is pivoted in bracket 127 of base 4, is pivoted at its upper end at 128. Intermediate its end it carries a pin 129 riding in a slot 128 of bracket 130 of the machine. The left-hand end of a restoring lever 130 is pivoted at 128. The restoring lever has a cam surface 131 which engages a bracket 132 attached to casting 3 and rides up on the bracket during the left-to-right movement of lever 130. During this movement head 133 of lever 130 will engage pin 134 of double-armed lever 92, assuming that the lever is unlatched, and will rotate it into position shown in Fig. 11, in which it will be latched by the latch 90. When lever 130 and its head 133 are in the position shown in Fig. 10, lifting of latch 90 will permit spring 93 to flip the double-arm lever 92 into the position shown in this figure.

The so-called "memory" device through which the setting of the selecting bars 44 during the feeding of one card is communicated to the tabulating and listing mechanism during the feeding of the succeeding card will now be described with reference to Fig. 3, which illustrates the apparatus with the carriage and selecting bars in the extreme left position. It will be noted that each selecting bar 44 carries near its left-hand end a pin 137 which is straddled by the forked end of a bar 138 which in turn is pivoted on a rod 139 supported in a casting 140 attached to base 4. The lower end of bar 138 has a key-slot cut-out 141, whereby it may be readily snapped on the bearing rod 139. Each plate 142 (one for each selecting bar 44) is frictionally held between the bar 138 associated therewith and a spring riveted to the bar at 143. As the selecting bars 44 are moved to the right into the positions determined by the perforations in the card fed, they will rock the associated bars 138 into various angular positions and the members 142, being frictionally held, will also be rocked into corresponding positions.

When the carriage reaches the extreme right position (Fig. 10), rods 145 and 146 mounted in brackets 147 (only one shown) rigidly attached to the left-hand end of carriage 26 will have aligned all members 142 in a vertical position, although the position of arms 138 may be in different positions, depending on the positions in which their associated selecting bars 44 were stopped by holes in the card last fed from magazine 2. Therefore, when the carriage is in the left-hand position and all of the arms 138 are aligned (because the selecting bars are aligned by bar 212 as elsewhere explained), the angular position of the members 142 with respect to their associated arms 138 is determined by the previous forward position of their associated selecting bars, which in turn is determined by the location of the holes punched in the various columns of the card just fed. On the next stroke of the carriage from left to right members 142 of selecting bars 44, which stop in the same position as on the previous stroke, will come to rest in a vertical position when their selecting bars are stopped, whereas the members 142 of selecting bars 44 which stop in a different position from that of the previous stroke, will be inclined to the right or left of the vertical position and the continued movement of the carriage will read-

just them to a vertical position by rods 145 and 146 as already described. In other words, any adjustment of the angular position of members 142 with respect to their associated arms 138 is evidence of a change in the position of the selecting bars 44 and in the position of holes in the card last fed as compared with the holes in the preceding card. Member 150 is a broad U-shaped piece extending across the machine, the upturned ends of which are pivoted at 151 to brackets 147 (only one shown) mounted one on each side of the left-hand end of the carriage, and held in position shown in Figs. 1 and 10 by spring 152, one end of which is attached to lug 154 of member 150 and the other end attached to unnumbered lug of bracket 147. Member 150 shown in section in Fig. 3 carries a member 149, the right-hand edge of which normally projects beyond the transverse section of member 150 and the right-hand edges of rods 145 and 146, so as to enter the slots 148 of members 142 as the carriage nears the end of its left-to-right movement, providing the slots are aligned with the members 142 all in a vertical position. However, if any member 142 is not in a vertical position (indicating that the card last fed differs from the preceding card as previously explained), the right-hand edge of member 149 will engage the left-hand edge of such members 142 (unless 149 is cut away as explained later) before rods 145 and 146 have restored it to the vertical position and cause member 150 to rotate in a clockwise direction against the tension of spring 152 on its pivot 151, causing member 153 also pivoted at 151 and supported against gravity by lug 154 of member 150, to drop so that notch 155 in its lower edge engages ear 156 of lever 157. The cutting away of that portion of 149 which extends to the right of bars 145 and 146 opposite member 142 associated with any given selecting bar makes that bar and its corresponding column of the card ineffective to cause the release of any crank 168 or 168' by dog 164 or 164'.

The continued movement to the right will, through lever 153, communicate motion to the upright lever 157 and cause it to rock from left to right around its pivot 158. The upper end of lever 157 engages the left-hand edge of a horizontal bar 159 and pushes it from left to right against the tension of a spring 160 fixed to the frame of the machine. During the travel of bar 159 from left to right it carries with it two levers 161 and 162, both of which are shown in Fig. 1, and only one, 162, of which is shown in Figs. 10 and 11. The levers 161 and 162 are centrally pivoted to the bar 159 and the lower ends of levers 161 and 162 will engage the lower ends 163' and 163 of dogs 164 and if the upper ends of levers 161 and 162 are stopped in their travel from left to right by matrix control lever 311A, as shown in Fig. 11, the functioning of which will be explained later. The dog 164 will be rocked in a counter-clockwise direction on its pivot 166 against the tension of a spring 167 and will release crank 168 connected to a gear pinion 169, in the form of pinion wire with ends turned down, extending across the machine. The identical arrangement is provided to cooperate with the pivoted lever 161. The crank corresponding to 168, which is controlled by a dog corresponding to 164, is mounted on a gear pinion 170 running clear across the machine.

The horizontal bar 159 initiates a total taking operation whenever blade 149 engages the edge 75 of one or more numbers 142 providing matrix

control lever 311A is so positioned as to engage the upper end of lever 162 pivoted on bar 159. The blade 149 is removable and its front edge is cut away except in those fields where a total should be taken in the event of any change in this field. This performs the automatic control feature to be described in greater detail. This cutting away removes that part of 149 (see Fig. 3) which extends to the right of rods 145 and 146 which would otherwise engage members 142 in 10 those positions in which control is not desired.

Just before the carriage reaches the extreme right-hand position, the pin 15 (Fig. 4) moves away from lever 51, permitting it to rise under the tension of spring 61. This forces up link 62, 15 turning lever 65 clockwise and lifting bracket 48 and matrix holder 46 above the level of the selector pins 45 on each of the selecting bars 44. This action clears the selecting bars so that they are free to move to the left with the carriage on 20 the return stroke.

When the carriage is in its extreme right-hand position, the machine is ready to print on a sheet of paper 171 (see Figs. 2 and 3) running the full width of the machine, indicia corresponding to 25 the perforations in the card last fed. At its left-hand end the upper face of each bar 44 carries types 172 formed therein corresponding to the indicia borne by the cards. Depending on the extent to which a bar 44 has been moved, one or 30 another type 172 will be positioned below the roller 173 on which the paper web 171 is carried. One arm 174 is provided on each side of the machine to carry the roller 173 which also extends the full width of the carriage. The arm 174 is 35 pivoted in the frame of the machine at 175. The arm 174 is formed into a bell-crank 176 to which is pivoted at 177 a link 178, the free end of which carries a link 179 held in the position shown in Fig. 2 by means of a spring 180 fixed to the 40 frame of the machine. The lower end of the link 179 is pivoted at 181 to a horizontal bar 182. A pin 183 provided on the carriage engages, during the last fraction of its movement from left to right, the link 179, and moves it against the tension of spring 180. Through link 178 and crank 176 the roller 173 will be rocked into the position shown in Fig. 2 in which the printing is accomplished. This happens provided that a lever 184 pivoted at 185 on bar 182 is obstructed by a 45 matrix control lever 186 (to be explained later) at the lower end, and by an ear 187 provided on the dog 68. If the lever 184 is free to move at one of its ends or at both ends, then the pin 183 will move through the lever 179 the bar 182 from 50 left to right, without causing crank 176 to rock, whereby the printing roller will remain in the position shown in Figs. 1 and 3, and the positioning of selecting bars 44 will not be recorded at this point.

In the extreme right-hand position of the carriage the card 1a is entirely out of the magazine and is held against members 31 by the roller 51 (see Fig. 5). The driving gear 13 (Fig. 3) has rotated approximately at an angle of 240°. 65 As driving gear 13 continues to rotate, it will move the carriage through linkage 16, 18, 19 from right to left. Owing to the fact that the rollers 51 are prevented from rotating in a clockwise direction, they will hold the card 1a in its 70 advanced position and, as the members 31 are pulled out from under the card upon the return of the carriage to the left, the card will be dropped into one of the pockets 96 or 97, depending on the position of the guide 95. As the 75

- arm 53 was pulled towards the magazine 2 by the spring 55 when the carriage moved to the left, the roller 52 swung with the arm and turned the card over the edge of bar 33 into a vertical position until the bar 33 traveled with the carriage farther to the left. Since the stop 56 prevents the bar 53 from traveling further, the roller will be arrested and the card will be permitted to drop into the selected pocket.
- 10 The selecting bars 44, no matter into what position they may have been moved during the left-to-right movement of the carriage, will travel back with the carriage, since the rollers 42 are free to fall back from the position shown in Fig. 15 into the position shown in Fig. 3 over the inclined surface 50. The selecting bars will continue to travel back with the carriage until a shoulder 211 (Fig. 3) formed in each bar engages a stop 212 which is mounted on the frame 20 and runs clear across the carriage. Owing to this, when the carriage has travelled all the way back to the left, all the bars 44 will be aligned and, of course, the pins 45 will also be aligned. The position of the stop 212 is determined so 25 that on the forward stroke the pin 45 will be stopped under the matrix hole corresponding to the perforation in the card being fed over the stop wires 34. When once set, the position of the stop 212 is permanent.
- 30 During the back stroke of the carriage from right to left the link 116 (Figs. 10 and 11) is not rotated on its pivot 117, since the lever 121 is in the position shown in Fig. 10 and permits the pin 112 to ride up in the slot 113 as the lever 126 is 35 rocked from right to left by link 98 which is carried at 23 by the carriage. The lever 121 was pushed into this open position by an ear 213 coming in contact with a stop 214 (Fig. 1) during the forward stroke of the machine. Lever 40 121 is held open by stop 214 until pin 112 rises in slot 113. Lever 121 cannot return until pin 112 again reaches bottom of slot which is at the end of the return stroke. Similarly, the lever 125 (Fig. 1) permits the pin 100 to ride up in the 45 slot 101, the lever having been swung into the open position by an ear 215 engaging a stop 216 near the end of the left-to-right movement of the carriage.
- 50 During the back stroke the right-hand end of arm 73 (Figs. 7, 8, 10 and 11) on lever 68 will be engaged by the lower end of a dog 217 held in the position shown in Fig. 10 by coiled spring 218. The dog will revolve about its pivot 219 on link 130' pivoted at 169, into the position shown in 55 Fig. 7. Lever 168 is then moved by said dog in a clockwise direction about its pivot 169 past a latch 220 pivoted at 166 against the tension of spring 167 which is common to latches 164 and 220 and normally tends to hold them against a common stop 221. Lever 168 will be moved to the position just described, whether it is in the position shown in Fig. 10 or in the unlatched position shown in Fig. 11. If lever 68 is not 60 latched up by dog 70 but is in the position shown in Fig. 11, dog 217 will not be rotated on its axis 219, but its forward movement by link 130' will restore lever 168 from the position shown in Fig. 11 to the position shown in Fig. 10. During the 70 backward movement of the carriage, bracket 147 carried members 150 and 153 from the position shown in Fig. 11 into the position shown in Fig. 1, thus permitting vertical bar 157 to be restored by spring 160 acting on bar 159, until the vertical 75 lever 157 hits against a stop 222.

The various elements are now back in the position shown in Fig. 3.

The machine as disclosed is equipped with two adding heads or units 250 and 251 (Fig. 3) adjustable across the width of the machine so as 5 to accumulate data from different groups of selecting bars 44. Head 250 is slidably mounted on square shaft 117 and head 251 on square shaft 105, one of the end plates of each head being indicated at 252 and 253, respectively. Only so 10 much of the mechanism forming part of each head is shown as is necessary for a clear understanding of the invention.

In each head, between side plates indicated as 15 252, is a square shaft 254, 255 rigidly carrying a pinion (not shown) meshing with a toothed arc 256 in head 250, and a similar arc in head 251. Since the details of the two heads are alike, the following description will be restricted to head 250.

In each head, between side plates indicated as 20 252, is a square shaft 254, 255 rigidly carrying a pinion (not shown) meshing with a toothed arc 256 in head 250, and a similar arc in head 251. Since the details of the two heads are alike, the following description will be restricted to head 250.

The arc 256 is rigidly connected with a bushing having a square hole and sliding on square shaft 117. The forward movement of the carriage oscillates, square shaft 117, through crank 116, first in a counter-clockwise direction and then in a clockwise direction. The counter-clockwise movement of square shaft 117 gives through toothed arc 256 a clockwise motion to square shaft 254 which, through frictional means (details not shown), moves eight toothed segments, one of which is shown at 258 and another at 259, in a clockwise direction. Each toothed segment 258, 259, etc., is mounted between spring washers with square holes fitting shafts 254 and 255. The spring washers are mounted on shafts 30 254 and 255.

Above the toothed segments 258 and 259 are a set of totalizer wheels 260 mounted between two brackets 261 pivoted at 262 in end plates of head 250. The position of these brackets 261 is determined by a lever 263 connected at one end to one of the brackets 261 and at the other end to crank 264 provided with gear teeth in mesh with pinion 169. Crank 264 is free to rotate around square shaft 117. As previously shown, pinion 169 is 40 connected with lever 168 and the position of the totalizer wheels 260 with respect to the toothed segments 258, 259, etc., is therefore determined by the position of lever 168 which may be latched by latch 220 or latch 164, or unlatched as shown 50 in Fig. 11. A spring 409 through bracket 261, lever 263, geared bell crank 264 and pinion 169 tends to move the lever 168 into the position shown in Fig. 11. If lever 168 is retained by latch 220 the totalizer wheels 260 will be in mesh with segments 258, 259, etc. If the lever 168 is held by latch 164, the totalizer wheels will be in a neutral position just clearing the teeth of the segments 258. When released by latch 164, the totalizer wheels will be thrown up against a print roll 265, 60 causing a record to be made on a strip of paper 266 suitably fed from a supply through a copying ribbon (not shown) by properly embossed characters on the periphery of the totalizer wheels 260. 65

During the latter part of the forward stroke of the carriage, when link 116 is drawn down by linkage of which 114 is a part, the segments 258, 259, etc., are rotated in a counter-clockwise direction by friction means previously referred to, 70 until arms 267, one pivoted to each segment, are moved downward to engage steps 268 on the individual selecting bars 44. The particular step that a bar 267 engages depends on the position to which the selecting bar 44 has been moved 75

during the left-to-right movement of the carriage which in turn is determined by the perforation occurring in the card that is being fed. The bars 267 communicate the setting of the selecting bar 44 through their associated segments like 258 to the totalizing mechanism.

The tens carry or tens transfer mechanism of the totalizer is shown in Fig. 16. Each number wheel 260 of the totalizer carries a pinion as shown for engaging its corresponding segment 258. It also carries a pin 405 which when the number wheel passed from "0" to "0" depresses the lower end of a bell crank 403, causing it to rotate in a counter-clockwise direction against the tension of spring 402. This movement unlatches lever 404 which in turn unlatches stop lever 400 pivoted at 401. The extent of the clockwise movement of the segments is determined by the ears in stop levers 400. When these levers are unlatched as above explained, their corresponding segments push them over to a stop which permits segments 258 to turn their corresponding number wheels one tooth farther than if levers 40 were latched in position shown in Fig. 16. The latches 403 and 404 associated with one number wheel unlatch the lever 400 associated with the segment 258 of the number wheel of the next higher order. In other words, if in Fig. 16 the number wheel 260 represents units, then the stop lever 400 determines the stopping position of segment 258 associated with the tens number wheel, and each time pin 405 on the unit number wheel depresses latch 403 as above described, the tens number wheel will be rotated one tooth farther, thus effecting the tens transfer or tens carry. Shaft 410 is mounted between brackets 261 and during its downward movement, when totalizer wheels next engage segments 258, 259, etc., will reset any released latches 404 to engage their respective latches 403. Shaft 410 also acts as a counter-clockwise stop for levers 400. Shaft 411 acts as a clockwise stop for levers 400. The angular displacement of levers 400 from position shown in Fig. 16 to engagement with stop shaft 411 enables segments 258, 259, etc., to rotate their respective totalizer wheels one tooth, thus effecting the tens carry.

It will be seen, therefore, that when the carriage with the selecting bars 44 is moved from left to right, the positions of the various selecting bars 44 will be registered by the setting of the various bars 267 in a pattern corresponding to the steps 268 in the selecting bars. This pattern represents the perforated pattern in the card that is being fed during this stroke from left to right. Since the bracket 261 is up when the segments 258, 259, etc., are thus rotated, their rotation cannot be communicated to the totalizing mechanism 260. Near the end of the return stroke (from right to left) of the carriage the bracket 261 is brought down as above described, assuming that the selecting pins 45 have all found holes in the matrix 47, whereby the totalizer 260 will be brought in mesh with the segments 258, 259, etc., ready to receive the data stored in these segments when they are next rotated in a clockwise direction during the early part of the next left-to-right movement of the carriage. In other words, the record or data from one card are entered or stored in the totalizer during the feeding of the next or following card.

This takes place in the following manner: When the carriage with the selecting bars 44 is again moved from left to right the linkage, consisting of links 98, 114, 126, will cause the rota-

tion of square shaft 117 in a counter-clockwise direction which, through gear sector 256, will cause the segments 258, 259, etc., to rotate in a clockwise direction. This rotation will give each of the totalizer wheels 260 an angular movement in a counter-clockwise direction corresponding to the number of teeth on the associated segment 258, 259, etc., which a particular counting wheel 260 engages during this restoring movement. This in turn depends on the particular step 268 with which the associated bar 267 may have come into contact. The setting of the totalizing wheel will, therefore, numerically correspond to the step 268 with which the associated bar 267 came into contact during the previous forward movement.

When link 116 has concluded its counter-clockwise rotation, there will be no further turning of the square shaft 254 in a clockwise direction and in this position a finger 270 mounted on the carriage (Figs. 1 and 8) will first unlatch the dog 70, permitting lever 68 to turn by gravity into the position shown in Figs. 8 and 11. This finger 270 will then engage the tip 271 of latch 220 permitting lever 168 to fall back against latch 164 (Figs. 8 and 10). This movement, as previously described, disengages the totalizer wheels from the segments 258, 259, etc., by causing brackets 261 to be elevated. The continued forward movement (left to right) of the carriage through the linkage just mentioned gives link 116 a clockwise rotation and square shaft 254 a counter-clockwise rotation until the respective arms 267 engage steps 268 to register the pattern of the new card that is being fed.

If, toward the end of the forward travel of the carriage, the pins 45 cannot penetrate through holes in the matrix, that is to say, if the perforations in the card that is being fed do not correspond to the perforations in the matrix, then the matrix holder 46 will not descend sufficiently to cause members 68 and 73 to be rocked into the position shown in Fig. 10. The dog 70 will not latch double-armed lever 68, 73 as shown in Fig. 10 and they will remain in the position shown in Fig. 11. Therefore, upon the return stroke the dog 217 will not engage the end of lever 73 as in the previous case, and lever 168 will not be carried back into engagement with latch 220. The totalizer 260 will not be thrown into engagement with 258, 259, etc., and, therefore, no accumulation will take place.

As long as it is desired to accumulate on the totalizer, the lever 168 remains latched by 220 during the time that the segments are turned in a clockwise direction by square shaft 254 (Fig. 3), as shown in Fig. 10. The lever 168 goes into the position shown in Fig. 11 only when it is desired to print the number accumulated on the totalizer and to reset the totalizer to zero. This is accomplished in the following manner: After the setting on the totalizer wheels has been printed on the paper ribbon 266, the lever 168 is moved from the position shown on Fig. 11 into engagement with latch 164 or 220 through the agency of the dog 217, as previously described. During this movement a link 273 (see head 251 in Fig. 3) pivoted at one end to one of the brackets 261 and to one end of a lever 274, pivoted to one of the side plates 251 at 275, gives lever 274 a counter-clockwise movement. Through link 276 pivoted to the other end of 274 and to crank 277, crank 277 is rotated about its pivot 278. A dog 279 on crank 277 engages a ratchet 280 giving it a counter-clockwise rotation which, through gears 406 and 407, resets the totalizer wheels to zero.

Suppose cards are sorted numerically by order number which is punched in columns 10 to 14, inclusive, member 149 will be cut away as explained opposite all members 142 except those associated with selecting bars which are controlled by holes in columns 10 to 14, inclusive. Now, whenever a card is fed whose order number differs from the order number of the preceding card, one or more members 142 in positions 10—14 10 will be positioned out of the vertical, causing the totalizer wheels to be thrown up by spring 409 against the paper 266 through the cooperation of members 149, 150, 153, 157, 159, 162, 163, lever 168, pinion 169, bellcrank 264, link 263, and 15 bracket 261.

Gear pinion 407 is attached to end of square shaft 408 which carries the totalizer wheels like 260 for head 250. These totalizer wheels are mounted on bushings between spring washers 20 having square holes which fit square shaft 408. The friction produced by these spring washers enables the clockwise rotation of shaft 408 to rotate the totalizer wheels in a clockwise direction until pins like 405, Fig. 16, engage the stop 25 on lower end of bell-crane 403. In this position the totalizer is reset to zero with all the zeros in a line opposite the paper 266.

Obviously, the functioning of the counting head 251 will be controlled in the same manner 30 as the functioning of counting head 250, but the control is by matrix 281 placed in a matrix holder 282 and cooperating with the second set of pins 283 provided on the selecting bars 44. The pattern of pins 283 is always the same as the pattern of pins 45, since the corresponding pins of each pattern are attached to the same selecting bar 44. The bars 267^a of counting head 251 take off the readings from steps 284 in the selecting bars which correspond to the steps 268. In this 40 manner, during a single operation, two different classifications or tabulations of the cards can be obtained, or as many more as there are counting heads like 250 and 251. Matrix 282 controls a bar 76' similar to 76, to the right-hand end of 45 which is attached a bell-crane 87' similar to bell-crane 87 (Fig. 10). This bar 76' is mounted directly behind 76 and its right-hand end is attached to a bell-crane 87' (Fig. 10). The bar can also be seen through notches in 76 under 50 head 251 and it is notched so as to cooperate with matrix 281 as 76 cooperates with matrix 47 to control sorting. This makes it possible to sort into pocket 97, (1) all cards which meet requirements of matrix 47; (2) all cards which meet requirements of matrix 281; (3) all cards which 55 meet requirements of matrix 47 and/or matrix 281.

This bar, 76', is controlled by a matrix control mechanism associated with matrix 281 of which 60 311x, Fig. 1, is one of the matrix control levers.

The matrix holder 282 is raised and lowered in the same manner as the matrix holder 46. The manner in which this is accomplished is best shown in Fig. 4, in which the bell crank lever 65^a 65 has been indicated, which is connected with the matrix holder 282 in the same manner as the bell crank lever 65 is connected with the matrix holder 46. The motion is transmitted to the second matrix holder 282 through a link 65^b one end 70 of which is pivoted to the lower end of the bell crank lever 65 and the other end being pivoted to the lower end of bell crank lever 65^a.

Referring now to Figs. 3, 13, 14, 15, the matrix 75 47, in addition to the holes for determining selection and tabulation, may have also notches cut

out in its side for exercising tabulating control. As shown in Fig. 13 the notch 300 in the edge of matrix 47 determines the position on the cards 1 from which a head such as 250 may accumulate numerical data registered on card 1. When the matrix 47 is inserted in the matrix holder 46, links 301, 301A, etc. (Fig. 3), which pivot on a rod 302 between the side frame 252 of counting head 250 are rotated in a counter-clockwise direction by turning a handle (not shown) which rotates shaft 303 in a clockwise direction. The ends 304 of levers 301 will be moved above the level of the matrix 47. The matrix 47 is now inserted in the holder 46 and the shaft is now turned in a counter-clockwise direction to permit members 301, 301A, etc., to drop until the ends 304 rest on the top surface of the matrix. The position of head 250 is now adjusted along shaft 117 until the levers 301 corresponding to the lowest digits of totalizer wheels 260 fill the 20 notch 300 in the matrix 47. The remaining levers 301 will still have their ends 304 resting on top of the matrix adjacent to the notch 300. A further counter-clockwise rotation of shaft 303 will lock the members 301 which did not fall through the notch, and these members will be held in the position shown for 301A. Members 301 and 301A are shown near the right-hand end of Fig. 3, the curved member 303A passes under the pointed ends of members 301 and 301A whose ends 304 30 do not fall in a notch of the matrix. Thus the only columns on the cards from which data may be added are those which correspond to the notch 300, Fig. 13. A ratchet on the upper side of each member 301 engages a notch in the corresponding segment 258, 259, etc., indicated in dotted lines in Fig. 3 at 306. The engagement of a notch 306 in a segment like 258 by the associated lever 301 will lock such segment and will prevent it from accumulating data from the 40 selecting bars 44 which have been displaced. The other segments, not thus locked, and which numerically correspond to the notch 300 cut in the matrix 47 will be free to operate in the manner previously described.

The matrix 47 may also be provided with notches like 310 along another one of its edges to control other functions of the machine.

Referring to Figs. 13, 14 and 15, each one of a plurality of matrix control bars 311, 311A, 311B, 50 pivoted on shaft 312 in bracket 313 (shown also in Fig. 1) carries pins 314, 315. The upper end of each bar is retained in one of two positions by jockey spring 316 mounted on the bracket 313. The edge of the matrix 47 in which notches 310 55 are cut is engaged by the free ends of bars 317 as the matrix is inserted in the matrix holder, i. e., from left to right as shown in Fig. 13. These bars, as best shown in Fig. 15, are slotted and are slidable on a member 318 mounted in the frame 60 313. The end 322 of bar 317^a engages pin 315 on lever 311. The end corresponding to 322 of the adjacent bar 317 is cut off as indicated at 321. Similarly, the lower end of bar 317^a, shown in Fig. 15, is cut off as indicated at 320.

Assuming, for instance, that a matrix control lever had been in a position with its upper end to the left of jockey spring 316. Then the insertion of matrix 47 into the matrix holder with an unnotched portion coming in contact with 317A 70 of 317A engages pin 315 of the matrix control bar, causing it to rotate in a clockwise direction to the position shown in Fig. 15. During this rotation pin 314 engages 317, causing it to move to the 75

left and to enter the notch in the matrix. Had there been no notch, the matrix could not have been completely inserted in the matrix holder and this would inform the operator that something is wrong. In such a case the matrix control bar will assume a position with its pointed end directly under the jockey spring 316. In other words, it is necessary to have a notch in front of one bar like 317 and 317A of each matrix 5 control bar 311, 311A and 311B. Before using a matrix it is therefore necessary for the operator to indicate by notches the functions which he wishes the machine to perform. In a similar manner the other bars alternately engage the 10 pins corresponding to 315 and 314 of the matrix control bars 311A, 311B, etc.

As shown in Fig. 1, the lower ends of bars like 311, 311A and 311X affect the operation of the tabulating machine during the travel of the carriage. The lower end of bar 311, for instance, engages in one position a notch 323 in bar 76, and in another position it is out of engagement with said notch. Therefore, depending on the 20 position of bar 311, the bar 76 will or will not be permitted to move from left to right when the lever 73 releases it at notch 75. As above described, when bar 76 is free to move, it controls the sorting of the cards, whereas when it is held back it will not sort the cards and all the cards 25 will fall in the same pocket. The notches 310 cut in the edge of the matrix will, therefore, permit sorting, provided the matrix indicates that sorting is desired, by causing the lifting of bar 73 to release bar 76.

30 The lower end of bar 311A prevents in one position the movement to the right of bar 162 pivoted to 159, and in the other position permits bar 162 to move to the right. When obstructed, the lower end of 162 engages end 163 of latch 164 and releases arm 168, which causes the totalizer 35 to print and clear out, as previously described.

There are, of course, matrix control bars similarly positioned to control functions. 311X, for instance, has its lower end 186 in the path of the 40 lower end of pivoted member 184 (Fig. 2) provided that it is rocked into one position by the associated bars like 317. If it is in the path of 184 it will, during the left-to-right travel of the carriage, cause bar 184 to rock on its pivot 185 45 in a clockwise direction provided the upper end of 184 is not obstructed by ear 187 on double armed lever 68, 73. If it is obstructed, then 183 will rock 179 on its pivot 181 and move bar 178 to rock bell-crank lever 174 counter-clockwise. Roller 50 50 173 will come down to print.

The following is a summary of the foregoing detailed description intended to give a better understanding of the operation and utility of this 55 type of tabulating machine, with particular reference to the time sequence shown in Fig. 17.

Assume a group of cards 1, Figs. 1, 5 and 12, in which each card carries indicia representing a 60 separate business transaction. This information may include (1) date of transaction, (2) merchandise classification, (3) cost of merchandise, (4) selling price, (5) salesman's number, (6) cash or charge transaction, etc. Assume also that the cards are arranged in numerical sequence by merchandise classification number. 65

70 Assume also that the following information is desired regarding the transactions represented by the group of cards without changing the arrangement of the cards:

(a) Total sales, i. e., the sum of the selling 75 prices indicated on the several cards;

(b) Totals of sales for each merchandise classification.

The matrices to determine (a) and (b) will have all holes punched 0-9, inclusive, in each column, since no selection is involved. In other 5 words, the selling price must be accumulated in each case. Therefore notch 300, Fig. 13, will be cut under the columns in which selling price is indicated. Since the arrangement of the cards is not to be altered, all cards must go into pocket 10 96 in the same order as they are arranged in magazine 2. This means that the sorting flipper 95 must be maintained in the position shown in Figs. 1 and 3. This is accomplished by locating notch 310 in edge of the matrices to determine 15 the information (a) and (b) so that 311B will engage notches 323 and prevent members 87 from engaging end 89 of latch 90 and releasing sorting flipper 95.

Likewise, since no printing is required on 171, 20 the matrix in holder 282 will have a notch in its edge to position 186 so that it will not be engaged by member 184. The matrix to determine 25 (a) will have a notch in its edge to position 311A so that it will not be engaged by the upper end of lever 162, whereas the matrix to determine (b) will be so notched as to position 311A in the path of 162. These two matrices which we will call A and B, prepared as above, are now inserted in matrix holders 47 and 282, respectively. A member 30 149 with its front edge cut away except in the positions opposite members 142 associated with selecting bars 44 corresponding to the columns on the tabulating cards in which the merchandise classification is indicated, is prepared and mounted 35 in the position shown.

The machine is now ready to start with the carriage 25 and selecting bars 44 in the position shown in Fig. 3 and indicated in time chart, Fig. 17, at 0. As the carriage moves from left to right, 40 the bottom card of group 1 is fed to the right. By the time the card has reached position 30 (Fig. 17), selecting feelers 34 have been released by plate 39 attached to the carriage and their ends 38 are pressing upward against the bottom of the 45 card that is being fed. As the carriage and bottom card continue to the right, hole positions 9, 8, 7, 6, 5, 4, 3, 2, 1, 0, 11 and 12 pass successively over the ends 38 of selecting feelers 34. When a 50 hole in one of the columns of the card reaches the position of ends 38 of feelers 34, the end of that feeler projects through the card and the continued movement of the card rotates member 35 clockwise on its bearing 36, causing roller 50 to engage a notch in selecting bar 44 and arrest its 55 motion. In this position pins 45 and 283 of that particular selecting bar 44 are under holes in matrix holders 47 and 282 which correspond to the position of the hole in the card being fed. The pins 45 and 282 will thus set up male patterns of 60 the holes in the card fed.

During the movement of the carriage from position 160 to 190 (Fig. 17) matrix holders 47 and 282 are lowered by pin 15 engaging lever 57 attached to link 62, Fig. 1. All of pins 45 and 283 65 find holes and, therefore, the levers 68 (one shown in Fig. 1 for matrix holder 46) are depressed and latched by latches 70 (Fig. 8). As previously described, this causes the transfer of numerical data from the selecting bars 44 through stop bars 267 70 and segments 258 to totalizer wheels 260 during the time indicated in Fig. 17 by the legend "Segments 258, 259, etc., up" during the next movement of the carriage from left to right. In other words, numerical data is transferred first from

the card being fed to the selecting bars 44, then from the bars 44 to the segments 258, and finally, from the segments to the totalizer wheels 60. This last transfer takes place during the next movement of the carriage from left to right.

As each succeeding card is fed from the magazine 2 to pocket 96, member 149 will enter slots 148 in members 142 during the time indicated in Fig. 17 by the legend, "Memory device test time," providing the numerical indication of the merchandise classification is the same as the previous card. When a change occurs in the merchandise classification, at least one member 142 will have its notch 148 out of line with the approaching member 149 which will engage the edge of one or more members 42, causing 160 to rotate clockwise about pivot 151 and cause notch in the lower edge of member 153 to engage ear 156 of lever 157, causing it in turn to move member 159 to the right. Since matrix B in matrix holder 282 is notched so as to position member 311^a (Fig. 11) in the path of the upper end of member 152 pivoted to member 159, whereby the left-to-right movement of 159 will cause the lower end of 152 to engage projection 163 of latch 164, this releases lever 168 and actuates the totalizer bracket 281 to rotate clockwise (Fig. 3) about pivot 282 (by tension of spring not shown), until the raised type numerals on the totalizer wheels print on paper strip 266 through an ink ribbon (not shown). The numerals are so arranged on totalizer wheels 260 that the number printed is the sum of numerical data transferred from cards fed to the totalizer as above described. This printing of the accumulated data occurs during the time indicated by "Print time" in Fig. 17.

During the next return stroke of the carriage from right to left, lever 168 is returned to latch 220 and during this return the totalizer is reset to zero. The above described operation has occurred only on adding head 251 because matrix B was so notched. Adding head 250 therefore accumulates a grand total of the selling prices for all merchandise classifications, while adding head 251 accumulates subtotals. Now if matrix B had been notched so as to position 166 in the path of member 164 attached to 159, a translation of each card would be printed on paper 171.

After the last card has been fed from the magazine and the machine has made at least one more complete cycle, the machine may be stopped. The totalizer of adding head 251 will have printed the last subtotal and cleared out, since the stroke after feeding the last card constitutes a change from the last merchandise classification indication. The totalizer of adding head 250 contains the grand total of all sales which should equal the sum of the subtotals printed in head 251, but printing this total has not yet occurred. This is done manually by the unlatching of arm 168 of head 250 after the last card has been fed. We now have the grand total of sales printed on paper slip 266 of head 250 and a list of subtotals for the various merchandise classifications printed on paper 266 of head 251. If the matrix B were notched to prepare a printed translation of all cards we would have a list of all transactions printed on paper 171.

The printed records may now be torn off and constitute, with the matrices A and B and the specially prepared memory member 149, a complete record of the tabulation. Matrices A and

B and memory member 149 may now be filed for similar use at later dates.

By way of illustrating the flexibility and utility of this machine let us assume that it is desired to determine the following information from the above mentioned group of cards without disturbing their arrangement:

1. Total sales by Salesman #7, including all merchandise classifications.

2. Total sales by Salesman #7 for each merchandise classification.

3. A list of all transactions by Salesman #7.

To secure the above prepare two matrices similar to A and B described above, except that in the column of the matrix corresponding to salesman number only #7 will be punched, and proceed as described above, using the same or a similarly prepared member 149. Since only hole 7 is punched in each matrix adding can only occur with respect to tabulating cards punched in the 7 position, in the column designating salesmen. If it is desired to remove from the file all cards of salesman 7, this may be done by notching one or both of the matrices on the end so that lever 311B will be disengaged from notch 323 in bar 76, thus causing all cards punched 7 in the salesman column to fall in pocket 97.

Many other combinations are possible but the above illustrates some of the possibilities. For example, on one adding head 250 it is possible to accumulate the total sales of one salesman for one or several merchandise classifications, while during the same run, on the other adding head, 251, one may accumulate the cash transactions of a given salesman or all salesmen in a given merchandise classification.

This application of the matrix principle to tabulating machines illustrates the fact that the individual tabulating cards may have a utility of place and the file of cards a utility of arrangement, since it is possible to tabulate information from any classification determined by the holes punched in the cards without disturbing the arrangement. While it is admitted that sorting is frequently the economical method, the necessity for sorting must be considered a limitation in a system which frequently robs the individual card and the card file of a part of its usefulness.

What I claim is:

1. In a machine of the character described, means for sequentially feeding record members, a plurality of selecting bars variably set under the control of each record member that is fed, means responsive to the setting of said selecting bars for establishing two male patterns each registering data borne by said record members, two holders for matrices, means for simultaneously applying each matrix in its holder to its corresponding male pattern to ascertain if agreement exists, a totalizer associated with each matrix, means dependent on the setting of said selecting bars for controlling the operation of said totalizers, and means responsive to the accordance of a matrix with the associated male pattern for causing the operation of the associated totalizer.

2. In a tabulating listing machine, means for listing information from record members bearing data, means for sequentially feeding said record members, a plurality of selecting bars variably set under the control of each record member that is fed, means responsive to the setting of said selecting bars for establishing two male patterns each registering data borne by said record members, two holders for matrices, means for simultaneously applying each matrix in its holder to its

corresponding male pattern to ascertain if agreement exists, a totalizer associated with each matrix, means dependent on the setting of said selecting bars for controlling the operation of said totalizers, means responsive to the accordance of a matrix with the associated male pattern for causing the operation of the associated totalizer, and means jointly controlled by the setting of said bars and by said matrices for actuating said listing means.

3. In a machine of the character described, a magazine for record members bearing indicia, means for sequentially feeding said record members, a plurality of selecting bars each provided with a plurality of pins, means controlled by each record member fed for displacing certain bars in one direction thereby setting said selector bars for said pins to form as many identical patterns representing the indicia borne by the record member that is fed as there are pins on a bar, means for displacing said bars in the opposite direction thereby destroying the patterns, a plurality of steps cut into each selector bar adjacent each pin thereon, a totalizer associated with each group of pins of a male pattern, means cooperating with the steps cut into the bars adjacent the associated male pattern for controlling the extent of operation of the associated totalizer, a matrix holder cooperating with each group of pins forming a pattern, and means dependent on the correspondence of a matrix with the associated male pattern to actuate the associated totalizer.

4. In a machine of the character described, a magazine for record members bearing indicia, means for sequentially feeding said record members, means controlled by the indicia and operable as each record member is fed for simultaneously setting up a plurality of duplicate male patterns, each pattern representing the indicia of the record member that is being fed, a plurality of holders for matrices, one for each male pattern, means for simultaneously applying each matrix in its holder to its corresponding male pattern to ascertain if agreement exists, a plurality of totalizers one for each matrix holder.

and means for actuating the totalizer associated with a matrix which agrees with the male pattern.

5. In a machine of the character described, a magazine for record members bearing indicia, means for sequentially feeding said record members, a selector comprising a plurality of bars each having a normal position and a plurality of actuated positions into which it may be set by said record members, means controlled by each record member fed for setting said selector bars into positions representing the indicia on the record member fed, means operative thereupon for resetting said selector bars into the normal position, said setting and resetting constituting one cycle of the machine, a totalizer, means controlled by said selector for operating said totalizer for each card as the succeeding card is fed during the succeeding cycle, means for thereafter printing from and zeroizing the totalizer, and means for operating said printing and zeroizing means during said succeeding cycle of the machine whenever the indicia on a record member fed during said succeeding cycle is different from the indicia on the record member fed during the preceding cycle.

6. In a machine of the character described, a magazine for record members bearing indicia, means for sequentially feeding said record members, a selector, means controlled by each record member fed for setting said selector, means operative thereupon for resetting said selector, said setting and resetting constituting one cycle of the machine, a totalizer, means controlled by said selector for operating said totalizer for each card as the succeeding card is fed during the succeeding cycle, means for thereafter printing from and zeroizing the totalizer, and means for operating said printing and zeroizing means during said succeeding cycle of the machine whenever the indicia on a record member fed during said succeeding cycle is different from the indicia on the record member fed during the preceding cycle.

PAUL M. RAINY.
